Primary Examiner — Keli L Hill*Assistant Examiner* — Harold E Blackwell, II(74) *Attorney, Agent, or Firm* — Hanley, Flight & Zimmerman, LLC**CLAIM**

The ornamental design for a "mountable plate," as shown and described in FIGS. 1-7.

DESCRIPTION

FIG. 1 is a perspective view of a mountable plate. FIG. 2 is a front view of the mountable plate of FIG. 1. FIG. 3 is a rear view of the mountable plate of FIG. 1. FIG. 4 is a right side view of the mountable plate of FIG. 1. FIG. 5 is a left side view of the mountable plate of FIG. 1. FIG. 6 is a top view of the mountable plate of FIG. 1; and, FIG. 7 is a bottom view of the mountable plate of FIG. 1. The features shown in broken lines form no part of the claimed design. The lighter solid lines denote surfaces and contours. Line shading is not surface ornamentation.
